FIG. 1 is a perspective view of an air compressor enclosure for an oil free compressor embodying the invention; FIG. 2 is a right side elevational view of an air compressor enclosure for an oil free compressor of FIG. 1. FIG. 3 is a left side elevational view of an air compressor enclosure for an oil free compressor of FIG. 1. FIG. 4 is a top plan view of an air compressor enclosure for an oil free compressor of FIG. 1. FIG. 5 is a front elevational view of an air compressor enclosure for an oil free compressor of FIG. 1; and, FIG. 6 is a rear elevational view of an air compressor enclosure for an oil free compressor of FIG. 1.

The present application is directed to the design illustrated in the drawings. The broken line portions of the disclosure are for illustrative purposes only and form no part of the claimed design.
